United States Patent Office

Des. 189,040

Patented Oct. 18, 1960

189,040

CHEST OF DRAWERS

Jan Lunde Knudsen, Boston, Mass., assignor to Heywood-Wakefield Company, Gardner, Mass., a corporation of Massachusetts

Filed Aug. 24, 1959, Ser. No. 57,258

Term of patent 7 years

(Cl. D33—6)

Fig. 1.

Fig. 2.

Fig. 3.

Fig. 4.

Fig. 1 is a front perspective view of a chest of drawers embodying my new design;

Fig. 2 is a face view of one of the large drawers, as viewed from the outside, but on a scale larger than that of Fig. 1; and

Fig. 3 is a fragmentary sectional view on the line 3—3 of Fig. 2.

Fig. 4 is a fragmentary sectional detail view on the line 4—4 of Fig. 1.

I claim:

The ornamental design for a chest of drawers, substantially as shown and described.
